**HINGED TRAY FOR A DRAWING TOY
OR THE LIKE**

Andrew M. Holland, Santa Monica, Joseph P. Morris,
Huntington Beach, and Martin I. Sheps, Palos Verdes
Peninsula, Calif., assignors to Mattel, Inc., Hawthorne,
Calif.

Filed Feb. 2, 1970, Ser. No. 21,202

Term of patent 14 years

Int. Cl. D21—99

U.S. Cl. D34—15

FIG. 1

FIG. 2

FIG. 3

FIG. 4

FIG. 1 is a perspective view of a hinged frame for a drawing toy showing our new design in an open position;

FIG. 2 is a perspective view of same, here shown in a closed position;

FIG. 3 is a right side view in section of same;

FIG. 4 is a left side view of same;

FIG. 5 is a rear view of same;

FIG. 6 is a front view partially in section of same;

FIG. 7 is a top plan view of same; and

FIG. 8 is a bottom view of same.

We claim:

The ornamental design for a hinged tray for a drawing toy or the like, as shown.
